(57) **CLAIM**

The ornamental design for an outer surface of a platform, as
shown and described.

DESCRIPTION

FIG. 1 is a perspective view of an outer surface of a platform showing my new design;

FIG. 2 is a right side elevational view of the outer surface of a platform of FIG. 1; the left side elevational view being a mirror image thereof;

FIG. 3 is a front elevational view of the outer surface of a platform of FIG. 1; and,

FIG. 4 is a top plan view of the outer surface of a platform of FIG. 1.

The broken lines represent that the pattern of the claimed design is repetitive throughout its length. The separation and bracket represent that the claimed platform is of variable width.
